UNITED STATES PATENT OFFICE.

GAETANO GIFFRE, OF CAPITOL VIEW, MARYLAND.

NON-SLIPPING LOW SHOE.

1,110,624.

Specification of Letters Patent. Patented Sept. 15, 1914.

Application filed June 12, 1914. Serial No. 844,692.

To all whom it may concern:

Be it known that I, GAETANO GIFFRE, a citizen of the United States, residing at Capitol View, in the county of Montgomery and State of Maryland, have invented certain new and useful Improvements in Non-Slipping Low Shoes, of which the following is a specification.

In the present style of low cut shoes, such as pumps and slippers, a great difficulty encountered has been to so fashion the upper as to cause the top marginal edge of the same to hug tightly to the sides of the foot and the heel, so as to prevent slipping up and down in walking, or gaping open at the sides, which allows gravel and dirt to get into the shoe. Many efforts to remedy this difficulty have been made, a prominent example of which is to incorporate in, or near, the heel of the shoe a piece of elastic rubber webbing which is designed to hug the ball of the heel. Numerous objections exist to this arrangement, among which I may mention the following: The exposed rubber webbing is in the way of the heel in putting the shoe on; it rubs and wears out the stocking, and also is itself worn out by friction.

My invention consists in means for overcoming these objections and still accomplishing the beneficial objects sought, and to that end it consists in a low shoe having incorporated in its upper along the top of its marginal edge, either along the sides or at the heel, a novel form of insert retainer consisting of two parts, viz: a casing or sheath of leather containing within the same a strip of elastic rubber webbing extensible in the direction of its length, the outer sheath of leather serving to completely inclose the strip of rubber elastic on both the inner and outer sides and being slitted throughout its surface with transverse slits which allow it to be extended as the rubber is stretched, and to again close up when on the foot to a smooth leather surface both inside and outside the shoe.

Figure 1 is a side view of a low cut shoe, showing my invention applied to the sides of the same. Fig. 2 is a similar view, showing my invention applied to the heel of a shoe. Fig. 3 is a cross section on line 3—3 of Fig. 1. Fig. 4 is a side view of a piece of the leather-protected elastic webbing in

normal contracted position. Fig. 5 is a view of the same when extended or stretched. 55

In the drawing, Fig. 1 shows at S the incorporation of my invention in the sides of a shoe, while Fig. 2 shows, at H, my invention applied to the heel of a shoe.

My invention itself consists in an insert 60 which may be applied in either of the above applications, or anywhere else, and the specific construction of this insert is shown in Figs. 3, 4 and 5, in which A is a strip of flexible leather, such as kid, which is a little 65 more than twice as wide as the insert. This strip is cut transversely with slits c extending practically over the entire area of the strip. This leather is then folded on itself along its middle line to form a sheath or 70 casing, and in it is laid longitudinally a strip of elastic rubber webbing B which is extensible in the direction of its length. This rubber webbing is permanently inclosed and retained in the sheath by a line of stitching 75 a along one edge only, the slits in the leather sheath being so arranged that they shall cross or cut in many places the fold or bend of the top of the insert, so as to allow its longitudinal elongation when stretched, as 80 seen in Fig. 5.

The insert strip is made in indefinite lengths, as in Fig. 4, and is to be wound in coils as a new article of manufacture to be cut off in lengths suitable to the application 85 made of it for general use in the trade.

The leather casing A, which forms the protecting sheath for the rubber webbing, is run continuously through cutting rolls to form the slits c in a simple, cheap and practical way, and, after the webbing B is laid therein, the casing is stitched along one edge a to retain the elastic webbing and make a complete article of manufacture for the purposes described. When a piece of 95 this protected elastic strip is cut off, it is applied either to the sides of the shoe, as in Fig. 1, or the heel of the shoe, as in Fig. 2, and its special value is as follows: When putting on the shoe its marginal edge may 100 be stretched, as in Fig. 5, to give easy entrance to the ball of the heel, and after the foot is within the shoe the insert closes up again its slits, as in Figs. 1 and 2, to hug tightly to the foot; and the outside of the 105 elastic insert has a practically continuous

leather face which may be polished with shoe polish to correspond to the rest of the shoe, and the inside of the insert is also a continuous leather surface which permits the heel to slip easily into place, avoids wear on the stocking, and also protects the rubber webbing from the effects of wear.

I do not claim broadly a piece of elastic webbing on the inner upper edge of a low shoe directly exposed to contact with the stocking, as I am aware that this is old, but

What I claim is:

1. A low shoe having along its upper marginal edge an insert composed of an elastic rubber webbing extensible in the direction of its length, combined with and inclosed within a casing of flexible leather to form a protecting sheath both inside and outside the shoe, said external casing being formed with transverse slits.

2. A low shoe having along its upper marginal edge an insert composed of an elastic rubber webbing extensible in the direction of its length, combined with and inclosed within a casing of flexible leather to form a protecting sheath both inside and outside the shoe, said external casing being formed with transverse slits, some of the slits being

disposed to cross the folded edge of the sheath and the lower edge of the insert being stitched to the body of the shoe.

3. As a new article of manufacture, an insert for the marginal edges of low shoes, consisting of a longitudinally extensible elastic rubber webbing inclosed within and provided with an external protective casing of flexible leather slitted transversely to the longitudinal axis of the elastic webbing.

4. As a new article of manufacture, an insert for the marginal edges of low shoes, consisting of a longitudinally extensible elastic rubber webbing inclosed within and provided with an external protective casing of flexible leather slitted transversely to the longitudinal axis of the elastic webbing, some of the slits crossing the fold or bend of the casing and the other edge of the casing being connected together to retain the elastic webbing.

In testimony whereof I affix my signature in presence of two witnesses.

GAETANO GIFFRE.
